DISPENSER FOR NAPKINS OR SIMILAR ARTICLES

Austin E. Cofrin, Green Bay, and Samuel N. Hope, Wauwatosa, Wis., assignors to Fort Howard Paper Company, Green Bay, Wis., a corporation of Wisconsin

Application June 28, 1946, Serial No. 680,306

4 Claims. (Cl. 312—62)

1

This invention relates to a dispenser for napkins or similar articles, and more particularly to a dispenser for napkins which are folded so that the length of one of the outer folds is substantially less than the overall length of the napkin when folded.

It is an object of this invention to provide a dispenser economical in its operation, since it permits the withdrawal of only one napkin at a time.

It is another object of this invention to provide a dispenser which exposes only a small portion of each napkin as it is moved into position for withdrawal.

It is a further object of this invention to provide a dispenser which presents a portion of each napkin prior to its being withdrawn from the dispenser in a manner permitting free access to that portion, each succeeding napkin being left in the same position as was held by the napkin preceding it prior to the withdrawal of the latter; which presents a portion of each napkin prior to its being withdrawn from the dispenser through an opening which, because of its novel construction, protects the exposed portion of each napkin from soiling while still in the dispenser; which may be readily opened and closed during a reloading operation; and which has a novel and simple pressure spring and plate construction for continual feeding of the napkins into dispensing position.

Further objects and advantages of this invention will become evident as the description proceeds, and from an examination of the accompanying drawings which illustrate one embodiment of the invention, and in which similar numerals refer to similar parts throughout the several views.

In the drawings—

Figure 1 is a perspective view of a dispenser embodying the features of the present invention.

Figure 2 is a sectional view taken on line 2—2 of Figure 1; and

Figure 3 is a perspective view showing the pressure plate and the resilient strip associated with same, with one side of the dispenser in open position.

Figure 4 is a view in horizontal cross-section of a portion of one of the end walls of the dispenser shown in Figure 1, the view being taken along the line 4—4 of Figure 1.

As shown in the drawings, the dispenser may be constructed having two oppositely disposed end walls through which the napkins are dispensed, the dispenser being formed with two identical halves. This, of course, is only one form

of a dispenser embodying the invention since it could be readily constructed so that the napkins would be dispensed through one or more of the vertical walls.

5 In the embodiment of the invention shown, the dispenser has the two side walls 1 formed integrally with the top wall 2. The lower edges of the side walls 1 are bent inwardly to form the flanges 3 which overlap and are secured to two opposite edges of the base plate 4. Secured to the other two edges of the base plate are the 10 hinges 5 to which are attached the end walls 6 which are thereby permitted to open outwardly. The end walls 6 have the perpendicular marginal flanges 7 which are formed to fit within the side walls 1 and the top walls 2 when the end walls 15 are in closed position.

The description which follows is confined to one of the identical halves of the dispenser illustrated, it being understood that it is equally applicable to both of the halves.

The inwardly upset portions 8 of the marginal flange 7 cooperate with the oppositely upset portions 9 of the spring latches 10 to normally maintain the end wall 6 in closed position, the marginal flange 7 entering between the spring latches 10 and the side walls 1 when the end wall 6 is closed. This arrangement allows the end wall 6 to be readily swung open when desired by applying the proper outward pressure to it.

35 The end wall 6 has the opening 11 therein, the upper marginal edge 12 of the opening being disposed substantially at the mid-point of the wall 6. The outer surface of the end wall 6 above the opening 11 has a generally convex disposition, as best shown in Figure 4, the marginal edges of that surface adjacent the top wall 2 and the side walls 1 being sharply rounded to form the flange 7, with the amount of curvature rapidly diminishing toward the center of the end wall 6.

40 The marginal edges of the opening 11 are folded inwardly to present a smooth, rounded edge. The upper marginal edge 12, in addition, has the form of a narrow lip extending outwardly from the adjacent portion of the wall 6. This upper edge is substantially horizontal throughout most of its length but curves sharply down at its outer extremities into the side marginal edges 13 of the opening 11 as shown in Figure 1. These side marginal edges 13 lie in a plane intersecting the end wall 6 along a line parallel to and below the horizontal center line of that wall, and intersecting the base plate 4. The side marginal edges 13 therefore extend obliquely inward from the upper marginal edge

12, rounding into the lower marginal edge 14 of the opening 11 at their lower extremities. The upper portions 15 of the side marginal edge 13 form a continuation of the narrow lip formed by the upper edge 12, the projection of the lip from the end wall 6 being gradually reduced as the side marginal edges 13 extend downwardly and inwardly as described, the lip terminating substantially at the midpoints of the side marginal edges 13.

The lower marginal edge 14 of the opening 11 curves inwardly throughout its length, the adjacent portion 16 of the end wall 6 immediately below the edge 14 being dished inwardly.

Thus the opening 11 is set in the end wall 6 at an angle to the vertical, as best shown in Figures 2 and 3, the lower edge 14 thereof being offset inwardly. In addition, the upper marginal edge 12 of the opening 11 has a generally convex disposition, as best shown in Figure 4, and the lower marginal edge 14 thereof has a generally concave disposition, as best shown in Figure 2.

The contours of the end wall 6 just described, in combination with the disposition of the opening 11, are designed to maintain the supply of napkins 17 or similar articles in a position permitting ready access to the short, outer fold 18 of the napkin adjacent the opening 11.

The pressure plate 19, shown in Figs. 2 and 3, is designed to aid in maintaining the napkins 17 in this position. This pressure plate is carried by the resilient strip 20 which urges it toward the end wall 6, the plate, in turn, urging the napkin 17 toward that wall. The resilient strip 20 is rigidly attached to the pressure plate adjacent the bottom edge 21 of the plate at the point 22, immediately below the lower end of the narrow outwardly curved ridge 23. This ridge has a breastbone shape and is positioned to exert a pressure on the napkins 17 which, in combination with the contours of the end wall 6 above described, causes the napkins to assume a convexed disposition throughout their upper portions (when viewed from outside the dispenser). This pressure is especially operative at the location of the opening 11, since the lower edge 14 of the opening is inwardly depressed and confines the lower portion of the napkins more closely than the convex portion of the end wall 6 above the opening. This lower edge 14 also operates to give the lower portion of the napkins a concave disposition.

This arrangement creates a reverse bend in the napkins with a concave disposition underlying a convex disposition above, all of which combines to cause the short outer fold 18 of the napkins adjacent the opening 11 to extend vertically down from the upper edge 12 of the opening and out of association with the inwardly bent portion of the napkins. The lower end 24 of the fold 18 is then in a position which permits free access to it by anyone desiring to withdraw a napkin from the dispenser. The inwardly dished portion of the end wall 6 permits ready grasping of the end 24 by one or more of the fingers and the thumb, since a finger or fingers may be easily inserted behind the end 24 and the thumb may then be clamped down on the finger or fingers, with the end 24 locked therebetween.

In the embodiment illustrated, the two depending resilient strips 20 are formed of one continuous piece of material which is bent to form two ends depending from a short, straight center section 25. This center section 25 is secured to the top wall 2 by the slotted plate 26

which is rigidly attached to the midpoint of the underside of the top wall 2 by the rivets 27. The depending strips 20 emerge through the slots in the plate 26 and are formed to normally urge the pressure plates toward the walls 6, as described above. The method of securing the strips 20 to the pressure plates 19 maintains them in a position which allows pressure to be applied by the ridges 23 to the napkins in the manner described above.

Each resilient strip 20 could, of course, be mounted independently of the other, the method of forming and mounting utilized here being only a matter of convenience.

15 The form of the pressure plate and resilient strip combination described above provides a very simple construction, which is nevertheless effective. This effectiveness is attained without the use of complicated, articulated joints between the plates and the supporting members, and between the supporting members and the top wall, which has been a common method used in the past. The need for separate spring members to urge the supporting members toward the side walls has also been eliminated.

20 As shown in Figs. 2 and 3, the base plate 4 has the upwardly turned, vertical sides 28 adjacent the inner surface of the side walls 1. These sides 28 are provided with the inwardly protruding tongues 29 which act as stops for the pressure plate 19 when there are no napkins between the plate and the end wall 6. The laterally extending portions 30 on each side of the pressure plate are positioned to meet and be restrained by the tongues 29 when the plate is in such an extreme outward position.

25 The overhanging character of the upper edge 12 in relation to the lower edge 14 of the opening 11 is particularly desirable from the standpoint of preventing soilage of the napkins while still 40 in the dispenser. Any foreign matter falling onto the dispenser from above will be prevented from entering the opening 11 by this feature. In addition, the depending lower end 24 of the fold 18 forms a screen for the opening 11 which is not contiguous with the remaining portion of the napkins adjacent the opening. Thus, any soiling that may occur will probably be confined entirely to this end 24 of the outermost napkin.

30 The drawings and the above discussion are not intended to represent the only possible form of this invention as mentioned above, in regard to details of construction. Changes in form and in the proportion of parts, as well as the substitution of equivalents are contemplated, as circumstances may suggest or render expedient without departing from the spirit or scope of this invention.

35 What is claimed is:

40 1. A dispenser for folded napkins and the like comprising a plurality of side walls, a top wall, and a bottom wall, one of said side walls having an elongated opening therein extending across said wall, said opening being disposed so as to expose the free end of the short outer fold of a napkin and the like within said dispenser adjacent to said opening, the portion of said wall above said opening and the upper marginal edge of said opening being curved outwardly and the 45 portion of said wall below said opening and the lower marginal edge of said opening being curved inwardly, a pressure plate within said dispenser having a central projecting portion protruding toward said opening and spring means depending 50 from said top wall adapted to urge said pressure

plate toward said side wall having said opening therein, said pressure plate in turn being adapted to urge a stack of napkins and the like disposed between said pressure plate and said side wall toward the latter.

2. A dispenser for folded napkins and the like comprising a plurality of side walls, a top wall, and a bottom wall, one of said side walls having an elongated opening therein extending across said wall, said opening being disposed so as to expose the free end of the short outer fold of a napkin and the like within said dispenser adjacent to said opening, the portion of said wall above said opening and the upper marginal edge of said opening being curved outwardly and the portion of said wall below said opening and the lower marginal edge of said opening being curved inwardly, a pressure plate disposed within said dispenser, a resilient strip depending from said top wall and being secured at its lower extremity to the lower portion of said pressure plate, said pressure plate having a centrally and vertically disposed convex ridge therein protruding toward said opening, said pressure plate being disposed within said dispenser so that said ridge in said plate and said opening are at substantially the same level and said napkins or the like are forced against said lower margin of said opening by said plate.

3. In a dispenser for napkins and the like, a wall having an elongated opening therein extending across said wall, one of the longitudinal margins of said opening and the portion of said wall adjacent thereto being curved outwardly, the other longitudinal margin of said opening and the portion of said side wall adjacent thereto being

curved inwardly, a pressure plate within said dispenser, and means adapted to urge said pressure plate toward said wall, said pressure plate having a centrally disposed convex ridge therein protruding toward said wall and being disposed transversely of said opening so that said napkins or the like are forced against said lower margin of said opening by said plate.

4. In a dispenser for napkins and the like, a wall having an elongated opening therein, the portion of said wall adjacent the upper longitudinal margin of said opening and said upper margin being curved outwardly, and the portion of said wall adjacent the lower longitudinal margin of said opening and said lower margin being curved inwardly the transverse margins of said opening being angularly disposed with respect to said wall, so that the lower portions of said transverse margins are offset inwardly, a pressure plate within said dispenser, and means adapted to urge said pressure plate toward said wall, said pressure plate having a centrally disposed convex ridge therein protruding toward said wall.
